DISPLAY SHAPE RETAINING DEVICE FOR GARMENTS

Anthony Masullo, Ozone Park, and Irving Rosenkranz and Abraham Taylor, New York, N. Y.

Application July 12, 1941, Serial No. 402,096

3 Claims. (Cl. 223—71)

This invention relates to display shape retaining devices for garments and more particularly is directed to an improved adjustable means for retaining the shape of shirts, sweaters, jackets and the like in an original smooth, folded, stretched condition so that the appearance thereof will be enhanced when exhibited for show purposes.

Among the objects of the invention is to generally improve devices of the character described which shall comprise few and simple parts that are readily assembled to form a compact structure, which shall be cheap to manufacture, which is easy and convenient to insert and remove from an originally smooth folded garment without crumpling or otherwise disarranging, and which shall be practical and efficient to a high degree in use.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown various possible illustrative embodiments of this invention:

Fig. 1 is a front elevational view of a shirt folded as it is originally delivered from the manufacturer, having inserted in a concealed position therein an improved adjustable shape retaining device constructed to embody the invention in practical use, adjusted to smoothly stretch the shirt front portion, the device being indicated in dotted lines;

Fig. 2 is a cross-sectional view taken on line 2—2 in Fig. 1, the folded shirt being indicated in dotted lines;

Fig. 3 is a front elevational view of the improved adjustable device removed from the shirt in its maximum expanded position;

Fig. 4 is a cross-sectional view taken on line 4—4 in Fig. 3;

Fig. 5 is a rear elevational view of the expanded adjustable device shown in Fig. 3, partly broken away to show the interior construction, and

Fig. 6 is a front elevational view showing the improved adjustable device in contracted position ready for insertion in folded garments.

It has been found that in displaying garments, such as shirts, sweaters, jackets and the like articles in show windows and counter exhibits in

the same original smooth folded condition as when they leave the manufacturer and are received by the retailer, particularly when placed in an upstanding or depending position, it is advisable to insert in such garments between the folds thereof a shape retaining device for holding the front of such garments in a smoothly spread condition so that the appearance thereof will be enhanced. Heretofore, cardboards, pins and the like have usually been used for such purpose, the insertion of which requires considerable time, patience and painstaking assembly, otherwise the folded garment will be unduly creased and rendered unfit for sale as first class merchandise. When using pins with cardboard to retain the smooth stretched folded condition of the front portion of the garment, pin holes and creases are invariably produced in other parts of the garment resulting in a reduction of the value of the garment after being so displayed and returned to stock so that such garments must have their sales price reduced as shopworn goods due to such handling. Losses and decrease in valuation will therefore be entirely eliminated by the use of the improved adjustable shape retaining device embodying the invention.

Referring now in detail to the drawing, 10 denotes an adjustable garment display shape retaining device constructed to embody the invention in a form suitable for inserting in a folded shirt S. Said shirt S may be originally folded in the usual well understood manner as delivered by the manufacturer to the retailer with the opposite sides E of the body and the sleeves (not shown) infolded to extend along the back side and the bottom portion U upturned so that the front portion F of the shirt S with the collar C appears as shown in Fig. 1, the device 10 being positioned behind the back and said front portion F, and embraced between the side fold portions E and upturned portion U as indicated in Fig. 2. The shirt S with the device 10 adjusted in the manner hereinafter described may now be used as a unit for exhibit, show windows or other display purposes.

The device 10 preferably comprises a pair of symmetrically shaped flat plates 11 and 12 which may be substantially of rectangular shape to conform to the shape of the contour front F of the folded garment S. The top border portions 11a and 12a of said plates 11 and 12, respectively, if desired, may have a slight taper corresponding to the upper part or shoulder portion of the shirt S as seen from Figs. 1, 3 and 6. Said plates 11

and 12 have their front surfaces 11b and 12b, respectively, disposed in a plane which is adapted to form a smooth supporting backing for the front portion F of the folded shirt S, said plates 11 and 12 being mounted for movement to and away from each other by a suitable pin and slot connecting means with the front surfaces 11b and 12b thereof retained in the same plane. Said pin and slot connecting means may include a circular disc member 13 firmly attached or forming an integral part of the plate 12, and as here shown extending rearwardly from the back side of said plate 12. Said disc member 13 preferably is located along the upper inner side edge portion 12b of the plate 12 inwardly of the upper edge 12a as is clearly shown in Figs. 3, 4 and 6. For retaining the plate 11 for limited sliding movement with respect to plate 12 the disc member 13 may have a radial slot or elongated opening 13a which extends outwardly at right angles with respect to said inner edge portion 12b of the plate 12, said slot 13a being adapted to receive a pin or dowel 14 carried by the plate 11 for sliding movement.

The periphery of the circular disc 13 provides a pivotal bearing on which a cam member 15 is rotatively mounted, there being provided a rear backing plate 16 spaced from the back side of the plate 12 to overlie the rear side of the disc and the cam member 15, a filler piece 17 being interposed between said front plate 12 and rear backing plate 16 serving as a spacer. The filler plate 17 is of sufficient thickness to permit the cam member 15 to freely rotate on the disc member 13. The rear backing plate 16 preferably extends from the inner side edge 12b of plate 12 just short of the outer edge 12c thereof but is made sufficiently wide to cover the underlying portions of the disc 13 and cam member 15. Said backing plate 16 may also be shaped to provide an outwardly projecting portion 16a to serve as an aligning abutment for the portion of cam member 15 extending beyond plate edge 12b and the adjacent cooperating portion of the front plate 11 as is seen from Figs. 3 and 5.

The front plate 11 also has a rear backing plate 18 which is mounted to said front plate 11 through an interposed filler piece 19. The rear backing plate 18 and filler piece 19 are preferably of the same thickness as the backing plate 16 and the filler piece 17, respectively. The pin or dowel 14 extends from the front plate 12 and through the slot opening 13a of the disc member 13 to the rear backing plate 16, thus forming the slot and pin connecting means so as to interlock the moving portions of the device 10 against separation. The backing plate 18 may be cut back at 18a to conform to the projecting portion 16a of backing plate 16.

The cam member 15 has substantially one-half thereof formed with a semi-circular shaped camming surface 15a which is concentric with the inner surface 15b which rotates about the disc member 13. The remaining portion 15c of the cam member 15 is wider than the portion adjacent to the surface 15a so that when outer bearing surface 15d of said portion 15c comes in contact with a surface 17a provided on the filler piece 17, the plates 11 and 12 are shifted apart and separated, thus forming an expanding adjustment for the device 10, the filler piece 19 being shaped to permit unrestricted rotation of the portion 15a between edge portion 19a thereof and the disc member 13, as is clearly shown in Figs. 3, 5 and 6. The cam member 15 may also

be provided with a suitably shaped extending portion 15d which serves as a finger piece for manipulating the rotation thereof.

Plates 11 and 12, disc member 13, cam member 15, filler pieces 17 and 19 and backing plates 16 and 18 may be constructed of so-called "plastic" sheet material or formed of any suitable stiff laminated structures, as for example, wood, paper, cloth, or the like sheet material.

The plate 12, disc member 13, filler piece 17 and backing plate 16 form a unitary section of device 10, while plate 11, filler piece 19 and backing plate 18 form another unitary section with the cam member 15 interlocking said two unitary sections. This interlockment, it is seen, interconnects the parts of the unit sections of said device 10 through the pin and slot connection means in the manner above explained, the disc member 13 permitting sufficient play to allow alignment of the outer edges 11c and 12c of the plates 11 and 12 respectively, to conform with any irregularities in the folding of the shirt side edge folds E, permitting a slight swinging movement about the pin and slot connection means.

With the parts constructed and assembled as above described and shown in the drawing, the practical application of device 10 will now be apparent. With the handle portion 15d of the cam member 15 swung in the position shown in Fig. 6, the device is in the contracted position and can be readily inserted in originally folded shirt S to take the concealed position shown in Figs. 1 and 2. By merely swinging the handle 15d of the cam member 15 from the position shown in Fig. 6 towards a position shown in Figs. 3 and 5, the unit sections are shifted apart and the device 10 expanded. The outer edges 11c and 12c of the plates 11 and 12 respectively, become self-aligning and the front surfaces stretch the shirt front F smooth as shown in Figs. 1 and 2. The friction of the cam member 15 between the disc member 13 and the surfaces 17a and 19a of the filler pieces 17 and 19, respectively, serves to retain any adjustment of the disc cam in an adjusted position of the device 10 for stretching smooth the front portion F of the folded shirt S.

To remove the device 10, the handle 15d is simply returned to the position shown in Fig. 6 and the device 10 removed from the folded shirt S without disturbing or otherwise disarranging the original fold thereof. The shirt S can then be returned to stock as first class merchandise in the same condition as received from the manufacturer.

It will thus be seen that there is provided a device whereby the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described the invention, we claim as new and desire to secure by Letters Patent:

1. A display shape-retaining device of the character described comprising a pair of flat plates having front surfaces lying in a single plane, interlocking means for shifting said plates apart a desired spaced distance after inserting the device between the folded opposite side edge and bottom portions of a garment with said sur-

faces, said interlocking means including a disk member rigidly extending from the rear surface of one of said plates, a cam rotatably mounted on the disc member, a slot and pin connecting means interconnecting the other plate and the disc member permitting shifting movement of the plates to and away from each other, and a bearing surface spaced from said slot and pin connecting means supported by the last mentioned plate for contacting the cam to shift said plates apart and for retaining the plates in an effective adjusted position between said garment folds, said cam coacting with the bearing surface and pin and slot connecting means being constructed and arranged to allow self-aligning movement of opposite edge portions of said plates with respect to each other within the garment folds for conforming with possible irregularities in said garment folds and for retaining the gar-

ment front portion smoothly stretched on said plate surfaces.

- 5 2. The display shape-retaining device defined in claim 1 in which said cam has a finger piece extending in a direction towards a top end of the device for rotating the cam, said finger piece terminating a short distance from said top end and within the edge border of said plates when the cam is located in an effective position.
- 10 3. The display shape-retaining device defined in claim 1 in which the slot of said pin and slot connecting means extends radially with respect to the disc for guiding the shifting movement of said plates in the direction of the length of said slot.
